(57) **CLAIM**

We claim the ornamental design for a case for mobile phone, as shown and described.

DESCRIPTION

FIG. 1 is a front, left and top perspective view of a case for mobile phone showing our new design;

FIG. 2 is a rear, right and bottom perspective view thereof;

FIG. 3 is another front, left and top perspective view thereof showing a stand of the case in an open state;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines depict portions of the case for mobile phone in which the design is embodied that form no part of the claimed design.

1 Claim, 9 Drawing Sheets
